LOUDSPEAKER-STAND COMBINATION

Norman Leonard Thomasen, 615 San Jose Ave.,
San Francisco, Calif. 94110

Filed Feb. 16, 1972, Ser. No. 227,013

Term of patent 14 years

Int. Cl. D14—01
U.S. Cl. D26—14 G

FIG. 1

FIG. 2

FIG. 3

FIG. 1 is a view in perspective of a loudspeaker-stand combination, showing my new design.

FIG. 2 is a rear elevational view thereof.

FIG. 3 is a sectional view taken along the line 3—3 in FIG. 2.

The top and bottom walls of the unit are identical, and so are the two side walls.

The characteristic feature of my design resides in the specific configuration of the pedestal support as best illustrated in FIGS. 1 and 2 of the drawings.

I claim:

The ornamental design for a loudspeaker-stand combination, substantially as shown and described.
